FIREARM CARTRIDGE MAGAZINE

Robert R. Krieger, Mount Clemens, Mich.

Application January 3, 1955, Serial No. 479,332

7 Claims. (Cl. 42—18)

This invention relates to firearms and particularly to a removable magazine assembly for rifles or the like.

Many makes of rifles today, particularly sporting rifles, are constructed with a built-in or permanent magazine. Such magazine comprises a magazine well which is built into the trigger guard assembly and is disposed directly below the receiver of the gun such that the topmost cartridge in the magazine is picked up by the bolt during its forward movement and carried into the chamber. The bottom of the well is closed by a floor plate with a cartridge spring follower secured to the plate. To load such magazines requires the retraction of the bolt, followed by the insertion of the cartridges down through the receiver and into the magazine. It is obvious that the gun is incapable of being fired during this interval and that it would be desirable to be able to load the gun without disturbing the bolt, and in a shorter length of time than is possible in the above described arrangement. If a live cartridge remains in the chamber and it is desired to load the magazine, it is necessary to retract the bolt with the consequent ejection of the live cartridge.

An object of this invention is the provision of a removable magazine which is adapted to replace the built-in magazine of the gun and which may be removed from the gun or replaced therein without disturbing the bolt or a cartridge in the chamber thereby facilitating the replenishment of an exhausted supply of cartridges in a much shorter time than is at present possible with the conventional construction above described.

Another object of the invention is the provision of a removable magazine adapted to fit many different makes of guns and which is received within the magazine well of the gun as a unit, the cartridge follower spring, cartridge follower, and floor plate being first removed.

A meritorious feature of the invention is the provision of a releasable magazine retaining catch adapted to hold the magazine in the gun and which catch is adjustable so that it will fit many different makes of guns and serve equally well with each to accomplish its intended function.

Another meritorious feature of the invention is the provision of spring means biasing the removable magazine outwardly of the gun such that when the magazine retaining catch is unlatched, the magazine will be urged out of the gun to a position where it may be easily removed by the operator.

An advantage of the invention resides in its function of enabling the operator of the gun to quickly replenish an exhausted supply of cartridges by removing an empty magazine and immediately replacing it with a fully loaded magazine.

Other objects, advantages, and meritorious features will more fully appear from the specification, claims, and accompanying drawing, wherein:

Fig. 1 is a cross sectional view through the portion of the firearm wherein my removable magazine is disposed;

2

Fig. 2 is a cross sectional view through the removable magazine taken just above the floor plate thereof;

Fig. 3 is a cross sectional view through the rear wall of the magazine well showing the latch disposed therein;

Fig. 4 is a cross sectional view taken on the line 4—4 of Fig. 1; and

Fig. 5 is a cross sectional view taken on the line 5—5 of Fig. 1.

My magazine assembly is adapted for use with many different makes and models of rifles or the like. In the drawing it is shown, for illustrative purposes only, in conjunction with a conventional rifle such as a modified Springfield model 1903. The rifle has a guard 10 secured to the stock 12 at the forward end by a screw 14 passing through a boss 16 mounted upon the forward tang 18 of the guard. The guard has a trigger bow 20, forward of which is the magazine well having front and rear walls 22 and 24 respectively and side walls 26. Because it is my intention to do away with the following elements, they are not shown in the drawings but are briefly mentioned. The well is conventionally closed at the bottom by a floor plate with a magazine spring mounted upon the floor plate and supporting a cartridge follower. The floor plate is conventionally held in place by a tenon which fits into the slot 30 in the front wall of the magazine well. The rear of the plate is held to the guard by a catch. To load the magazine well the cartridges are pressed down through the receiver 28 into the well, the bolt being retracted. Such loading is a rather slow operation.

In Fig. 1 my improved magazine assembly is shown as mounted in the guard 10 of the firearm. The conventional floor plate, cartridge follower spring, cartridge follower, and floor plate latching means have been removed from the guard. My assembly comprises the magazine proper 34 and the latching device 36. The magazine includes a box-like receptacle assembly having a front wall 38, a rear wall 39, side walls 40, with the bottom of the receptacle closed by a floor plate 41. The top of the receptacle is open and the upper edge of the side walls converges at 42 to hold the cartridges in the magazine. The floor plate is secured to the receptacle with the periphery of the plate extending beyond the walls of the receptacle as at 43, to abut the guard as shown in Figs. 1 and 4.

Disposed inside the receptacle is a magazine spring 44 and a cartridge follower 45. The spring and follower are adapted to urge cartridges in the magazine upwardly against the converging lips 42. The magazine will hold a plurality of superposed cartridges, with the topmost cartridge in a position to be picked up by the bolt during its forward movement and carried into the chamber.

The magazine also includes a kick-out spring 46, which is secured to the floor plate as at 47. The spring is generally V-shaped in configuration. The ends of the spring extend through apertures 48 in the lower end of the rear wall 39 of the receptacle as shown in Figs. 1, 2, and 4. The floor plate is channeled as at 49 and 50 such that the ends of the kick-out spring will be depressed into the channels by the guard when the magazine is inserted into the magazine well as shown in Figs. 1 and 4. Without these channels or grooves, the floor plate would be spaced down from the guard by the thickness of the spring when the magazine is inserted in the well.

The kick-out spring is tensioned upwardly away from the floor plate and biases the magazine outwardly, or downwardly, of the guard when the receptacle is disposed in place in the magazine well. The ends of the kick-out spring abut the lower edge of the guard as shown in Figs. 1 and 4. When the magazine is unlatched from the guard, the spring moves the magazine outwardly of

the well a distance such that the operator may grasp the magazine and extract it completely from the guard.

The magazine is adapted to be used with many different makes of rifles, the dimensions of the magazine wells of which vary somewhat, particularly the dimension between the front and rear walls, such as front and rear walls 22 and 24 in the drawings. In order to adapt the magazine to these different sized wells it is necessary to provide some means for adjusting the magazine to fit the well so that the magazine will not shift forwardly or rearwardly in the well. In order to prevent such shiftable movement of the magazine I have provided a novel adjustment element shown at 50' in the drawings.

The adjustment element comprises a cam member 52 mounted on the floor plate rearwardly of the rear wall 39 of the receptacle. It will be noted that the floor plate extends beyond the rear wall 39 of the receptacle such that the cam may be mounted on the floor plate spaced from the wall 39. Such portion of the floor plate extending rearwardly of the wall 39 of the receptacle is shown in Fig. 2 and indicated at 53. The cam 52 is held in place by a rivet or the like which is provided with a slotted head 56 overlying the bottom surface of the floor plate, and a stem portion 58 which extends through the floor plate and is secured to the cam. The cam and rivet are fastened together in such manner that the floor plate is gripped between the head 56 and the cam 52. The rivet may be turned through the use of a screw driver or like tool. Such turning movement is resisted by gripping engagement of the floor plate between the cam and the head of the rivet with the result that the cam will remain in the position to which it is rotated.

The cam is provided with a bearing face 60. As the cam is revolved it is moved linearly of the floor plate with the result that the bearing face 60 is also moved. Such movement of the cam during its rotation may be termed as a movement toward and away from the receptacle. The cam is received, as shown in Figs. 1 and 5, within the base portion 62 of an L-shaped recess formed in the rear wall 24 of the magazine well. The upstanding leg of the L-shaped recess is indicated at 64. This recess is conventional and normally houses the floor plate latch means. The bearing face or camming surface of the cam 52 is adapted to bear against the rear wall 63 of the portion 62 of the recess and urge the magazine forwardly in the guard such that the wall 38 of the receptacle abuts the wall 22 of the magazine well.

In order to adjust the cam, the magazine is inserted in the guard with the receptacle disposed in the well. By use of a screw driver the cam is rotated to urge the magazine to its forwardmost position in the guard. In such position the front wall 38 of the receptacle will bear against the front wall 22 of the magazine well. Thereafter the magazine may be removed from the guard and the cam will be in a position such that when the magazine is later replaced in the guard, it will assume a position which is the same as that to which it has been adjustably moved during its initial positioning in the guard. The cam will thereafter need no further adjustment.

My novel latch means 36 in combination with the adjustable element 50' securely holds the magazine in the guard with the receptacle firmly or snugly positioned in the well. The latch is adjustable, as hereinafter explained, so that it will fit different makes of rifles. The distance between the surface 66 and the lower surface 68 of the guard varies slightly among the different makes of rifles, and the latch accommodates these varying dimensions.

The latch comprises a spring metal leaf 70 provided at the lower end with a hook-shaped portion 72 adapted to extend through an aperture 74 in the portion 53 of the floor plate, and overlie the lower surface of the plate forwardly of the aperture. The upper end of the leaf is enlarged and bored and tapped as at 76 to receive the

threaded stem 78. The stem is provided with a shoulder 80 adapted to bear against the top wall 82 of the upstanding leg portion 64 of the L-shaped recess. The stem above the shoulder extends through an aperture in the top wall of the recess as shown in Fig. 4. The stem is radially bored to receive the pin 84 which overlies the surface 66 of the guard. The shoulder 80 and the pin 84 prevent axial movement of the stem. The upper end of the stem is provided with a screw driver slot 87.

The leaf 70 is provided with a flat face 86 along its forward edge, and a pin 88 extending through the guard is adapted to abut this face and prevent rotation of the leaf. The lower end of the hook portion 72 is beveled forwardly upwardly as at 89. The leaf 70, because formed of spring metal, is capable of flexible movement toward and away from the magazine well. It is flexibly tensioned such that when it is pressed rearwardly by the operator of the gun and thereafter released, it will snap forwardly again.

It is now apparent that upon rotation of the stem 78, the position of the hooked portion 72 below the lower surface 68 of the guard may be adjusted. Because the lower surface of the hook 72 is beveled as at 89, when the magazine is inserted in the guard, the forward edge of aperture 74 will abut the bevel 89 and urge the hook rearwardly permitting the magazine to be fully seated against the guard in the position shown in Fig. 1. It will be noted that the leaf 70 with the hooked end portion 72 depends from the firearm with the hooked portion depending below the floor plate when the magazine is received in the guard. When the magazine is in the position shown in Fig. 1, the hook will slip forwardly over the forward edge of the aperture 74 to grip the floor plate against the surface 68 of the guard and hold the receptacle of the magazine in the well.

It will be noted in Fig. 1 that a space exists between the rear walls 39 and 24 of the receptacle and magazine well. If it were not for the adjustable element 50' the magazine would shift rearwardly with the result that the front wall of the receptacle would be spaced from the front wall 22 of the magazine well. As a result of this, the forward end of the magazine would tend to drop away from the lower surface of the guard and the floor plate would not be held securely in the position shown in Fig. 1. My novel latch means and the cam cooperate to hold it tensioned securely against the guard with the receptacle in place in the well. With the cam rotated to a position such that the magazine is urged to its forwardmost position, and with the hook 72 of the latch engaged over the forward edge of the aperture 74, the magazine cannot shift downwardly either at the forward or rearward end thereof.

In order to release the magazine from the guard, the operator presses rearwardly against the hook 72, moving it to a position such that it is disposed completely within aperture 74, whereupon the kick-out spring forces the magazine outwardly of the well. A very slight downward movement of the magazine will carry the floor plate below the hook 72, after which the hook may be released by the operator and the magazine grasped and completely extracted from the guard.

What I claim is:

1. A magazine assembly for a firearm having a magazine well comprising, in combination: a box-like receptacle closed at the bottom by a floor plate and removably receivable within the magazine well of the firearm; a latch mounted on the firearm and depending therefrom and adjustable toward and away from the firearm and engageable with the floor plate adjacent one end thereof to hold the receptacle in the well, a spring mounted on the floor plate and tensioned upwardly to abut the firearm when the receptacle is received in the well and bias the receptacle outwardly of the well, and an element mounted on the floor plate for adjustable movement longitudinally of the floor plate and adapted to abut a portion of the fire-

arm to position the receptacle in the magazine well against one end wall of the well.

2. A magazine assembly for a firearm having a magazine well comprising, in combination: a box-like receptacle closed at the bottom by a floor plate extending beyond the opposite end walls of the receptacle and adapted to abut the firearm and limit the insertion of the receptacle in the magazine well, a spring secured to the floor plate interiorly of the receptacle and projecting out of the receptacle through a wall thereof and adapted to abut the firearm, said spring tensioned upwardly away from the floor plate to bias the receptacle outwardly of the well, and latch means mounted on the firearm with a hook-shaped part depending below the firearm and received through an aperture in the floor plate to extend beyond the bottom surface of the plate and be releasably engaged over such surface of the plate to hold the magazine in the well.

3. A removable magazine for a firearm having a magazine well comprising, in combination: a box-like receptacle assembly having front, rear, and opposed side walls, and including a floor plate the marginal edges of which extend beyond the walls around the receptacle with the assembly adapted to hold a plurality of cartridges and be slidably removably received in the magazine well of the firearm with the marginal edges of the floor plate overlying the firearm adjacent the well; a spring secured to the floor plate with a portion disposed within the receptacle and extending outwardly therefrom and another portion overlying the margin of the floor plate outwardly of the walls of the receptacle to bear against the firearm adjacent the magazine well when the receptacle is received within the well; an inflexible element mounted on the receptacle assembly for adjustable movement forwardly and rearwardly of the assembly to abut a portion of the firearm to position the receptacle assembly in the magazine well with an end wall of the assembly abutting an end wall of the well; and latching means releasably coupling the receptacle assembly to the firearm at that end of the assembly opposite the end wall thereof abutting the end wall of the magazine well.

4. A removable center-feed magazine for a bolt-action staggered feed firearm having a chamber, a guard, and a downwardly opening magazine well in the guard comprising: a box-like receptacle having front, rear, and opposed side walls, and closed at the bottom by a floor plate the marginal edges of which extend outwardly beyond the walls of the receptacle to overlie the guard adjacent the well when the receptacle is inserted in the well; one of said marginal edges extending rearwardly beyond the rear wall of the receptacle; a cartridge follower spring in the receptacle; the upper edges of the side walls of the receptacle provided with inwardly extending lips to retain cartridges in the receptacle against the action of said spring and permit successive guided movement of cartridges out of the receptacle in alignment with the chamber of the firearm; inflexible adjustable camming means secured to said rearwardly extending marginal edge of the floor plate rearwardly of the receptacle to engage a portion of the guard and position the forward wall of the receptacle against the front wall of the magazine well; and latch means for releasably coupling the rear end of the floor plate to the guard to hold the receptacle in the well.

5. A magazine assembly for a firearm having a magazine well and a downwardly opening recess rearwardly of the well comprising, in combination: a box-like re-

ceptacle closed at the bottom by a floor plate having a portion extending beyond an end wall of the receptacle and adapted to close the mouth of the recess in the firearm when the receptacle is received in the magazine well, 5 an element mounted on said portion of the floor plate for adjustable movement toward and away from the receptacle and receivable within the recess of the firearm to abut a wall of the recess when the receptacle is received in the well and position the receptacle snugly against an end wall of the magazine well, an adjustable latch mounted on the firearm within the recess and provided with a downwardly extended threaded stem with a hook-shaped part threadedly coupled with said stem with the hook depending below the firearm to be received through an aperture in the floor plate adjacent the element, 15 said hook-shaped part being threadedly adjustable on said stem toward and away from the firearm, said hook-shaped part intermediate its opposite ends being a leaf spring flexibly tensioning the hook toward a position of engagement over an edge of the aperture to releasably hold the receptacle in the magazine well.

6. A magazine assembly for a firearm having a magazine well therein comprising, in combination: a box-like receptacle closed at the bottom and removably receivable within the magazine well of the firearm, and a latch mounted on the firearm and depending therefrom and having a part adapted to engage the underside of the receptacle and which part is selectively threadedly adjustable vertically with respect to the underside of the receptacle and resistingly movable longitudinally of the firearm toward and away from the well to engage the underside of the receptacle to hold the same in the well.

7. A magazine assembly for a firearm having a magazine well comprising, in combination: a box-like receptacle closed at the bottom by a floor plate extending beyond the opposite end walls of the receptacle and adapted to abut the firearm and limit the insertion of the receptacle in the magazine well, a spring secured to the floor plate interiorly of the receptacle and projecting out of the receptacle through a wall thereof and adapted to abut the firearm, said spring tensioned upwardly away from the floor plate to bias the receptacle outwardly of the well, and latch means mounted on the firearm and having a floor plate engaging part tensioned toward the magazine well opening, said part having a lip portion disposed to underlie the floor plate when the receptacle is fully seated in the well, and said part having a camming surface cooperable with the floor plate to cam the part out of the path of the floor plate as the receptacle is inserted in the well and prior to complete seating in the well.
